VERTICAL EDGING MILL

Florence C. Biggert, Jr., Crafton, Pa., assignor to
 United Engineering & Foundry Company,
 Pittsburgh, Pa., a corporation of Pennsylvania

Application June 25, 1937, Serial No. 150,254

9 Claims. (Cl. 80—31.1)

This invention relates to mills, generally known as vertical edging mills, for rolling the edges of metal blanks such as slabs and the like. As such mills and their uses are known to those skilled in the art, it is believed unnecessary to go into a general description of them here. However, one of the difficulties encountered in connection with vertical edging mills is the tendency for the blanks passing through a mill to climb upwardly on the periphery of one or both of the rolls and to thereby get out of line with the pass of the rolling mill to which they are being delivered.

It is an object of this invention to provide a vertical edging mill in which blanks are held down on the work-supporting means on which they travel through the mill.

The invention is illustrated in the accompanying drawings in which Fig. 1 is a view of the entry side of my vertical edging mill with half of it shown in vertical section; Fig. 2 is an enlarged view of the edging mill taken on line II—II of Fig. 1; and Fig. 3 is a diagrammatic view showing a modification of this invention.

Referring to Figs. 1 and 2 of the drawings, a pair of horizontally spaced housings 1 is rigidly mounted on a suitable foundation or bed-plate 2 with their central portions connected by parallel horizontal rails 3 secured to opposite sides of the housings. Disposed between these rails 20 in sliding engagement with their inner faces is a pair of carriages 4 which are suspended from the rails by integral lateral projections 6 that rest on the rails, as shown in Fig. 2.

The two carriages are moved toward and away from each other by means of horizontal adjusting screws 7 that are detachably connected to their outer surfaces. As shown in Fig. 1, the screw for each carriage is threaded in an interiorly threaded gear 8 journaled in the upper portion of the adjoining housing. This gear is rotated, to move the screw lengthwise, by a pinion 9 which is driven by a motor 11 mounted on a bracket 12 secured to the outer face of the housing. The two edging rolls 13, which are supported by the carriages in a manner about to be described, are moved toward and away from each other by carriages 4 in order to form suitable edging passes for blanks of different widths between them.

It is a feature of this invention that the mill is constructed for preventing blanks from climbing up the periphery of one or both of the edging rolls and thereby rising off the work-supporting means on which the blanks travel through the mill, or off the collars 14 on the lower ends

of the rolls. Accordingly, means is provided for effecting relative inclination between the work-supporting means and the axes of the rolls in vertical planes extending longitudinally of the work-supporting means. In the preferred embodiment of the invention shown in Figs. 1 and 2 this relative inclination is obtained by tilting the rolls, as shown by the broken lines in Fig. 2, so that as the rolls rotate they constantly urge a blank 16 down on the work-supporting tables 17 and 18, or against collars 14.

Each roll is normally journaled on a substantially vertical axis in upper and lower arms 19 projecting laterally from a frame 21 (Fig. 1) which is so associated with the adjoining carriage 4 as to be rotatable on an axis transverse to the tables. For this purpose the frame is preferably slidably connected to the carriage, each carriage having an inwardly projecting portion 22 in which there is a downwardly extending arcuate groove 23 disposed in a plane substantially parallel to the longitudinal axis of the tables. The bottom of the frame is in the form of a segment 24 which is slidably disposed in this groove. The frame has an outwardly projecting portion 25 26 near its upper end provided with a downwardly extending flange 27 the lower surface of which is concave. This flange is slidably disposed in a cooperating recess 28 in the upper portion of the carriage. Consequently, the frame 21 can be rotated relative to the carriage 4 the desired number of degrees with its flange and segment sliding in the grooves in the carriage, the arcuate grooves and flanges having as their common center the point about which the frame 35 rotates. When the two frames are thus inclined or tilted in planes substantially parallel to the longitudinal axis of the tables, the edging rolls journaled in the frames are likewise inclined relative to the tables.

To rotate or tilt the frames the upper end of each one is provided with a toothed segment 31 which meshes with a pinion 32 mounted on one end of a shaft 33. This shaft is journaled in a housing 30 and is turned by a worm gear 34 which is rotated by a worm 35 driven by a motor 36 mounted on a bracket 37 attached to one side of the housing. The motors are reversible so that the frames and rolls can be tilted in either direction longitudinally of the tables, the direction of inclination depending upon the direction in which blanks are passing through the edging mill.

As it may be desirable to vary the degree of inclination of the rolls in accordance with the

- thickness of the blank passing between them, means is provided for indicating the number of degrees the rolls are inclined in either direction. Therefore, on the outer end of each shaft 33 there is a bevel gear 38 meshing with a similar gear 39 to which one end of a pointer 41 is rigidly connected. The free end of the pointer moves across a plate or dial 42 which is calibrated to indicate the number of degrees that the edging rolls are inclined relative to the tables. These pointers are, of course, actuated when pinions 32 are rotated to tilt the frames and rolls. Housing 30 is clamped on top of the carriage by clamping plates 20 (Fig. 2) bolted to the carriage. By loosening these clamping plates the housing can be slid away from frame 21 to remove pinion 32 from segment 31, and the frame with its roll 13 can then be lifted bodily from the carriage by a crane hook engaging eye 25 connected to the frame.
- Each edging roll is preferably driven from its lower end through universal couplings of known design allowing ample angular disalignment. In the exemplary embodiment for the sake of simplicity wobbler connections are shown including a wobbler 43 rotated by a gear 44 journaled in a casing 46 secured to the lower portion of the adjoining carriage. Each gear is turned by a pinion 47 which is driven from below by a bevel gear 48 that in turn is driven by a bevel pinion 49 journaled on a horizontal axis in the casing. The two bevel pinions for the two rolls are splined on a common shaft 51 which is driven from one end of the mill by a motor 52.
- In the embodiment shown in Fig. 3, each edging roll 61 is journaled on a vertical axis in fixed bearings connected to a horizontally adjustable carriage 62, and work-supporting tables 63 and 64 are so mounted that they can be inclined longitudinally relative to the roll axes. This inclining of the tables may be effected in various ways, but the upper surfaces thereof are maintained in a common plane at all times. The drawings illustrate one way of inclining the tables according to which links 66 are pivotally suspended from the opposite ends of each table with their lower ends pivoted to the upper arms of bell-crank 67. The cranks are pivotally mounted on suitable supports 68, and their lower ends are all pivotally connected to a single rod 69 which may be reciprocated by a piston 71 in a fluid pressure cylinder 72. The cranks on the two sides of the mill face in opposite directions so that when rod 69 is moved into the position shown in full lines the outer end of table 64 is raised and the outer end of table 63 is lowered, while when the rod is moved to the right the outer end of table 64 is lowered and the outer end of table 63 is raised. Blanks are delivered to and from the tables while the tables are in horizontal position.
- The degree of inclination of the tables relative to the roll axes may be indicated on a calibrated dial 73 by a pointer 74 which is operated in any suitable manner from one of the bell-crank that tilts the tables. The direction in which the tables are tilted will depend on the direction in which a blank is passing over them. Due to the relative inclination between the tables and the roll axes, blanks are held down on the tables.
- According to the provisions of the patent statutes, I have explained the principle and mode of operation of my invention and have illustrated and described what I now consider to represent its best embodiment. However, I desire to have it understood that, within the scope of the appended

claims, the invention may be practiced otherwise than as specifically illustrated and described.

I claim:

1. A vertical edging mill comprising means for supporting blanks as they pass through the mill, a vertical edging roll journaled on each side of said means, and means for effecting relative inclination between the roll axes and said supporting means in vertical planes extending longitudinally of said supporting means whereby to hold blanks down on said supporting means. 5

2. A vertical edging mill comprising means for supporting blanks as they pass through the mill, a vertical edging roll journaled on each side of said means, means for effecting relative inclination between the roll axes and said supporting means in vertical planes extending longitudinally of said supporting means whereby to hold blanks down on the supporting means, and means for indicating the degree of said inclination. 20

3. A vertical edging mill comprising means for supporting blanks as they pass through the mill, a pair of horizontally spaced rails extending transversely of said means, a pair of carriages disposed between the rails and suspended therefrom, the carriages being slidably mounted at opposite sides of said means, means for adjusting the carriages toward and away from each other, a vertical edging roll carried by each of said carriages, means for driving the rolls, and means for effecting relative inclination between the roll axes and said supporting means in vertical planes extending longitudinally of said supporting means whereby to hold blanks down on said supporting means. 25

4. A vertical edging mill comprising means for supporting blanks as they pass through the mill, a vertical edging roll journaled on each side of said means, and means for tilting said rolls in vertical planes extending longitudinally of said supporting means whereby to hold blanks down on said supporting means. 40

5. A vertical edging mill comprising means for supporting blanks as they pass through the mill, a vertical edging roll journaled on each side of said means, means for tilting said rolls in vertical planes extending longitudinally of said supporting means whereby to hold blanks down on the supporting means, and means for indicating the degree of said tilting. 45

6. A vertical edging mill comprising means for supporting blanks as they pass through the mill, a carriage disposed on each side of said means, a frame mounted on each carriage for rotation on a horizontal axis transverse to said means, means for rotating said frames a predetermined number of degrees, and an edging roll journaled in each of said frames and thereby being adapted to be tilted for holding blanks down on said supporting means. 55

7. A vertical edging mill comprising means for supporting blanks as they pass through the mill, a carriage disposed on each side of said means, a frame slidably connected to each carriage for rotation in a vertical plane extending longitudinally of said supporting means, one end of each frame being provided with a gear segment, a pinion meshing with each segment, means for driving said pinions, and an edging roll journaled in each of said frames and thereby being adapted to be tilted for holding blanks down on said supporting means. 60

8. A vertical edging mill comprising means for supporting blanks as they pass through the mill, a carriage disposed on each side of said means, a frame slidably connected to each carriage for rotation in a vertical plane extending longitudinally of said supporting means, and means for effecting relative inclination between the roll axes and said supporting means in vertical planes extending longitudinally of said supporting means. 75

nally of said supporting means, one end of each frame being provided with a gear segment, a pinion meshing with each segment, means for driving said pinions, an edging roll journaled in each of 5 said frames and thereby being adapted to be tilted for holding blanks down on said supporting means, said rolls being the sole means for positively urging said blanks downwardly, a calibrated dial associated with each carriage, and a pointer associated with each dial and operatively connected to 10 each pinion for indicating the amount of rotation of the adjoining frame.

9. A vertical edging mill comprising an edging roll, a frame for supporting said roll, and a driving mechanism for tilting the edging roll in the direction of the pass through the mill in order to urge blanks downwardly, said driving mechanism being slidably laterally to permit withdrawal from the mill of the edging roll and its supporting frame as a unit. 5
